UNITED STATES PATENT OFFICE.

ARCY H. JOHNSON, OF PULASKI, TENNESSEE, ASSIGNOR OF ONE-HALF TO CYRUS C. HOUSTON, OF LEWISBURG, TENNESSEE.

TELEPHONE REPEATER OR RELAY.

1,207,051

Specification of Letters Patent.

Patented Dec. 5, 1916.

Application filed February 12, 1916. Serial No. 77,959.

To all whom it may concern:

Be it known that I, ARCY H. JOHNSON, a citizen of the United States, residing at Pulaski, in the county of Giles and State of Tennessee, have invented certain new and useful Improvements in Telephone Repeaters or Relays, of which the following is a specification, reference being had to the accompanying drawings.

10 This invention relates to certain improvements in telephone repeaters or relays and it is primarily an object of the invention to provide novel and improved means whereby it is possible and practical to employ, in connection with long distance telephone systems, conductors of ordinary galvanized iron wire in lieu of the copper lines now employed, whereby the cost of installing a long distance telephone system is 20 materially reduced.

It is also an object of my invention to provide novel and improved means wherein the line is divided into a plurality of talking sections, each constituting a local circuit and wherein each of said sections is 25 operatively connected by my improved relay or repeater, said relay or repeater substantially constituting a combined receiver and transmitter, whereby the sound undulation conveyed by one line section may be 30 transmitted to a second line section.

Furthermore it is an object of my invention to provide a novel and improved repeater or relay wherein the talking circuit 25 is normally closed and whereby said circuit is automatically opened during signaling operation, it being understood that the signaling current is of greater voltage than that of the talking current.

40 Another object of the invention is to employ galvanized iron wire as the line conductor which is extended such a distance that when the resistance of the conductor causes the current to drop perceptibly or the attenuation too great for good telephonic transmission to place or insert a relay or repeater at that point. A second line of wires is then strung another equal distance and so on over the entire line, bridging in 53 as many phones as desired along the line and making allowance for the resistance of each phone.

The invention consists in the details of construction and in the combination and arrangement of the several parts of my im-

proved repeater or relay whereby certain important advantages are attained and the device is rendered simpler, less expensive and otherwise more convenient and advantageous for use, all as will be hereinafter 60 more fully set forth.

The novel features of the invention will hereinafter be definitely claimed.

In order that my invention may be the better understood, I will now proceed to describe the same with reference to the accompanying drawings, wherein—

Figure 1 is a diagrammatic view illustrating an embodiment of my invention; Fig. 2 is an enlarged sectional view taken through my improved relay or repeater as herein embodied; Fig. 3 is an elevational view, detached, of the bridge piece and carbon chamber with their concomitant parts, as included in my improved relay or repeater as herein disclosed; and Fig. 4 is a view in top plan of my improved relay or repeater as disclosed in Fig. 2.

As disclosed in Fig. 1, 5, 6, 7 and 8 denote the main lines of adjacent line sections, 80 said lines being formed preferably of galvanized iron and R and R' denote relays interposed in a conductor of each line section and adapted to be operated by a signaling device of any conventional type such as a regular hand generator or telephone magneto.

The relay R shown at the right hand of Fig. 1 is provided with a winding 9 which may be of any usual or customary type. 90 This winding is positioned upon a core 10 which is preferably provided so that it has one polar projection at least. This winding, as shown, is connected in series with the line wire 6. Adjacent one of the polar 95 extremities of this relay there is positioned an armature 11 which may be secured to the lever 12 in any suitable manner. This lever which also includes a lever 13, preferably disposed at substantial right angles, is provided with contacts adjacent its free end. At the juncture of the two levers, they are 100 preferably pivoted as shown by the pivoted connection 14. The contacts mounted upon the lever 13 are adapted to engage and contact with the stationary contacts 15, 15^a and 16. The line wire or conductor 6 continues to the left and is connected to or with the pivot 17 at the left.

The relay R' is preferably constructed in 110

the same manner as the relay R. It has a winding 18 and a core 19. Positioned adjacent one of the core extremities is an armature 20 which is mounted on or carried by the lever 21. This lever is provided with a lever 22 which has mounted upon it suitable contacts. Where the two levers join, they are pivotally mounted as indicated at 17. As the lever 12 is to be positioned away from contact with the pole extremity of the core 10 a suitable spring or other resilient member 23 is provided and for the lever 21, the spring or resilient member 24 is also provided. Thus the armatures 11 and 20 are maintained away from the poles of the relays. The lever 22 and its contacts are adapted to engage with and contact with the stationary contacts 25 and 26 and 26^a.

20 At some point on the conductor 6, between the relay R and the pivot 17, there is tapped a conductor 27 which is connected to one pole of a battery B. The other side of this battery is connected to the transmitter by means of the conductor 28 which leads to the terminal 29. The other terminal 30 of the transmitter is connected to the transformer T by means of the conductor 31. As shown, this conductor 31 connects 25 with the primary winding T^p of this transformer and the other end of the primary winding is connected to the conductor 6, as indicated at 32. From this point or tap 32 the conductor 6 continues on to the 35 pivot 17.

The line conductor 5 is connected directly with the windings of the receiver of the relay A. Leading from the other terminal of the relay is the conductor 33 which connects with the secondary winding T^s of the transformer T. The other terminal of this transformer winding T^s is connected to the contact 25 by means of the conductor 34. As shown at the left, the lever 21 is pulled 40 away from the core 19 of the relay R' so that the lever 22 is making contact with the stationary contact 25. This is its normal position. As shown at the right, the relay R has just attracted its armature 11 and thereby the lever 18 has moved away 45 from the contact 16 and has made contact with the contacts 15 and 15^a. The talking 50 circuit is thus open.

At a point between the battery B and 55 the terminal 29 the conductor 35 is tapped on to the conductor 28 at the point indicated at 28^a. This conductor 35 leads to a stationary contact 36 which is adapted to engage or contact with a suitable contact formed on the vibrator v. This vibrator may be of any usual type or construction and is preferably of a low frequency or its frequency is substantially equal to that of the frequency of the ordinary type of polarized telephone bell.

The induction coil H may be formed with the usual primary winding H^p and a secondary winding H^s. One end of the primary winding H^p is connected to the vibrator v. The other terminal of the winding is connected to the contact 15 by means of the conductor 37. The secondary winding H^s has one of its terminals connected to the conductor 37 or to one terminal of the primary winding H^p. This secondary winding H^s is connected to the line wire 7 by means of the conductor 38 at a point indicated at 39. The induction coil H is provided with the usual laminated iron core 40.

The contact 16 is connected to the secondary winding T^s of the transformer T' by means of the conductor 41. The other terminal of this secondary winding is connected to one terminal of the relay A' by 85 means of the conductor 42. The other terminal from the relay A' is connected to the line conductor 7. The conductor 43 is connected to the winding 18 on the core 19 of the relay R'. To the other terminal 90 of this winding the line conductor 8 is connected.

At some point on the conductor 43, the secondary winding T^s of the transformer T' is connected as indicated at 44. The 95 other terminal of this primary winding is connected by means of the conductor 45 to one terminal 46 of the transmitter portion of the relay A. The other terminal 47 is connected to the battery B' by means 100 of the conductor 48. Leading from the other terminal of the battery is the conductor 49 which is connected to the conductor 43 at the point indicated at 50. The conductor 51 connects the terminal 26 with 105 the primary winding H^p of the induction coil H'. The other terminal of this primary winding is connected to the vibrator v' in any convenient manner.

The vibrator v' is preferably of a similar 110 type to that described for the vibrator v and is provided with a suitable contact. The contact 52 is adapted to coöperate with the contact on the vibrator v'. Leading from this contact 52 is a conductor 53 which 115 is connected to the conductor 48 between the battery B' and the terminal 47 of the transmitting portion of the relay A, at 42^a. The secondary winding H^s has one terminal connected to the conductor 51 at or 120 adjacent the terminal or connection for the primary winding H^p. The other terminal of this secondary winding is connected to the line conductor 5 by means of the conductor 54 at a point indicated by the number 125 55.

The relay or repeater A is provided with a suitable shell 56 which may be of any desired form and also may be composed of insulating material. As shown in Fig. 9, 130

it is provided with a cap 57 which has suitable screw threads formed therein to co-operate with threads cut upon the shell 56 adjacent one end. Disposed within this shell and passing through a suitable aperture 58 may be the line conductor 5 and the conductor 33. These conductors are connected to the windings upon the electro-magnets 59 and 60 in any suitable manner. To support the electro-magnets 59 and 60 at a predetermined point, the inner casing 61 is provided which is adapted to be secured between the cap 57 and the shell 56 by means of the flange 62. To co-operate with the electro-magnets 59 and 60, there is provided a suitable permanent magnet 63 which is of the usual type and form as employed in the ordinary telephone receiver, which is shown as being of U-shape in Fig. 2.

The electro-magnets 59 and 60 are provided with the usual projecting cores which are spaced the usual or proper distance from the diaphragm 64. This diaphragm 64 is held in engagement with the inner casing 61 by means of a suitable annular ring 65 formed on the cap 57. To the diaphragm 64 is connected the transmitter of the type shown in Figs. 2, 3 and 4 which is preferably of the solid back type. The front portion of the electrode chamber 66 is connected to the diaphragm 64 in the usual or customary manner. One form of means being by a screw and a plurality of nuts 80. The back portion of the electrode chamber 67 is secured to the bridge piece 68 in any convenient way, one form being that indicated in Fig. 2, which comprises a bushing 69 to co-operate with the stem 70 formed on the back portion of the electrode chamber 67. This bushing 69 is preferably insulated from the bridge piece 68 by means of mica washers indicated at 71. The lower end of this bushing 69 is provided with suitable screw-threads and to co-operate with these threads is a nut 72. Thus the bushing may be readily secured within the aperture formed in the bridge piece 68. This bushing may be provided with a suitable boss 73 which is provided with a suitable hole through which passes a screw 74. The screw 74 is adapted to contact with the projecting stem 70 of the back portion of the electrode chamber. The front and back portions of the electrode chamber 66 and 67 respectively are provided, upon their inner walls, with threads to operate with the ring 79. The electrode chambers have positioned upon their inner faces a suitable insulating medium which may be mica, in the form of a washer. Thus the back portion of the electrode chamber 67, when connected to the front portion of the electrode chamber, by means of the ring 79, forms a chamber in

which are disposed the electrodes 75 and 76. These electrodes 75 and 76 are preferably carbon disks and disposed between them is a layer of carbon granules 79.

The terminal 46, shown in Fig. 1 which 70 is of similar construction and position to that of 30, is more particularly shown in Figs. 3 and 4, where they are indicated by the numeral 46. In Fig. 4, only one of the transmitting portions is shown and the numeral 46 has been assigned to the terminal. This terminal communicates directly with the back electrode 75. The front electrode 76 is connected by means of the jumper 77 to the terminal 47. The terminal 47 corresponds to the terminal 29 and they are similar in character and form. To secure the bridge piece 68 to the cap, any suitable means may be employed, one of which is indicated by the screws 78.

In practical operation, assuming a signal is being received that might be caused by the ringing current of a generator disposed at a central station or other point to the right of the diaphragm shown in Fig. 1, the 90 impulses would be received upon the line conductors 5 and 6. The relay R is shown as having been operated so that the armature 11 has been attracted to the core 10, by means of the winding 9. The lever 12 95 has been pulled downward against the action of the spring 23 and the lever 13 has been put into contact with the stationary contacts 15 and 15^a. The conductor 6, after leaving the relay winding, continues on to 100 the left until it connects with the pivotal connection for the levers 21 and 22, which are shown as positioned normally, the lever 22 making contact with the stationary contact 25. The armature 20 has not yet been 105 actuated upon by the winding 18 of the relay R' through the core 19. The circuit then is continuous from the line conductor 6 to the pivot 17, the lever 22 and the contact 25. The current then flows through the conductor 34 to the secondary winding T' of the transformer T, thence through the conductor 33 to the relay or repeater A and thence outward on the line conductor 5. The lever 13 is now making contact with the stationary contact 15 and from this contact 15 runs the conductor 37 leading to the primary winding H^p of the induction coil H. The primary winding is connected to the vibrator v which has contact with the stationary contact 36 and from this latter contact 36 the conductor 35 is connected to the conductor 28 at the point indicated by 28^a. The secondary winding H^s of this induction coil H has one terminal connected to the conductor 37 and the other terminal of this winding is connected to the conductor 38 which is tapped to the line conductor 7 at the point 39.

An additional contact 15^a is positioned ad-

10 jacent the lever 13 but spaced from the contact 15. This contact 15^a is connected to the line conductor 6. Tracing out the circuit from the battery B, the current will pass through conductors 28 and 35, contact 36 to the vibrator *v*, through the primary winding H^p , thence through the conductor 37 to the lever 13, through the supplementary contact 15^a to the line wire 6, and then through the conductor 27 to the other side of the battery. This will complete the circuit through the primary of the induction coil H . As the circuit is closed, the vibrator *v* will vibrate and interrupt the circuit which will produce a high tension current in the secondary H^s that will impress itself upon the conductor 38 connected to the line conductor 7 at the point 39. The signaling current is thus augmented by the action of the vibrator *v* and this current is impressed on the line conductors 7 and 8 through which it flows to the next point or relay station. The return through the line conductor 8 passing through the windings 18 of the relay R' , will cause the core 19 to attract the armature 20 which will break the talking circuit by causing the lever 22 to break the connection it made with the contact 25. From the relay winding 18 which is connected to the conductor 43, the circuit is then completed back to the pivot 14 to the lever 13, to the contacts 15 and 15^a. Both of the talking circuits are now open because of the signaling impulses passing through the relays R and R' . When the signaling impulses cease, the armatures 11, and 20 are pulled away by means of the springs 23 and 24 acting on the levers 12 and 21, respectively. The talking circuit is then reestablished as the levers 13 and 22 engage with the contacts 16 and 25, at which time the induction coils H and H' are cut out.

Assuming that the line conductors 5 and 6 are carrying currents caused by sound waves, such as would be made by a person speaking into the well known type of transmitter, these currents would actuate the relay or repeater *A*. These currents, in passing through the windings of the electromagnets 59 and 60, disposed in relay *A*, will cause the diaphragm 64 to vibrate according to the current variations. As the diaphragm 64 vibrates, it causes the electrodes 75 and 76 to change their spaced relation which alters the pressure upon the carbon granules 79. This change of pressure causes a change of resistance in the carbon granules and this alteration of resistance, which corresponds to the vibrations of the diaphragm causes a current to pulsate through the primary winding T^p of the transformer T . As the current leaves the receiving portion of the repeater or relay *A*, it passes on and through the secondary winding T^s of the transformer T to the contact 25, thence to the lever 22 to

the line conductor 6. The action of the transmitter upon the primary winding T^p induces a current in the secondary winding T^s of the transformer T which circulates through the conductor 41 to the contact 16 and in the other direction through the conductor 42 through the windings on the electro-magnets in the receiving portion of the repeater or relay *A'*, thence outward to the line conductor 7. Thus it will be seen that the first action or any voice actuated impulses arising on the line conductors 5 and 6 will be upon the repeater or relay *A* which will actuate the transmitting portion, causing changes in the transformer T' to be forwarded to the line conductors 7 and 8 in an amplified state.

I claim:

1. In a telephone repeater, the combination of a main line divided into line sections, each section comprising a normally closed talking circuit, a coacting transmitter and receiver connecting adjacent line sections, and automatic means for opening and closing the local circuits when signaling and voice impulses are impressed on the main line.

2. In a telephone repeater, the combination with a main line comprising a plurality of local talking circuits, a combined receiver and transmitter connecting adjacent line sections, a relay interposed in one of the main lines and normally maintaining the talking circuits closed, said relay operating to open the talking circuits when a signaling current is impressed on the main lines, the relay serving to direct the local circuit through a coil when the talking circuits are open, said coil having its secondary winding electrically connected with the main line of an adjacent line section.

3. In a telephone repeater, the combination with a main line comprising a plurality of local talking circuits, a combined receiver and transmitter connecting adjacent line sections, a relay interposed in one of the main lines and normally maintaining the talking circuits closed, said relay operating to open the talking circuits upon a signaling current being directed through the main lines, said relay when the talking circuits are open serving to direct the local circuit through a coil, said coil having its secondary winding electrically connected with the main line of an adjacent line section, the primary winding and circuit therefor including a vibrator of low frequency and a source of electric energy.

4. In a telephone repeater, the combination with a main line comprising a plurality of local talking circuits, a combined receiver and transmitter connecting adjacent line sections, a relay interposed in one of the main lines and normally maintaining the talking circuits closed, said relay operating

to open the talking circuits upon a signaling current being directed through the main lines, and when the talking circuits are open the relay serving to direct the local circuit 5 through a coil, said coil having its secondary winding in electrical connection with the main line of an adjacent line section whereby, when the talking circuit is open, the relay will close the circuit through the secondary 10 winding of the coil to the main line of the adjacent line section to relay the signaling current from one line section to another.

5. In a telephone repeater, the combination with a main line divided into line sections, each section comprising a plurality of local talking circuits, a combined receiver and transmitter connecting adjacent line sections, a relay interposed in one of the main 15 lines and normally maintaining the talking circuits closed, and electrical connections coacting with the battery of the local circuits and the relay when the talking circuit is 20 circuits closed, and electrical connections coacting with the battery of the local circuits and the relay when the talking circuit is

open for relaying the signaling current from one line section to another.

6. In a telephone repeater, the combination with a main line divided into line sections, each section comprising a plurality of local talking circuits, a combined receiver and transmitter connecting adjacent line sections, a relay interposed in one of the main 25 lines and normally maintaining the talking circuits closed, and electrical connections coacting with the battery of the local circuits and the relay when the talking circuit is 30 open for relaying the signaling current from one line section to another, said last named electrical connections comprising a signaling coil including a vibrator.

In testimony whereof I hereunto affix my signature in the presence of two witnesses. 40

ARCY H. JOHNSON.
